United States Patent Office

Des. 179,956
Patented Mar. 26, 1957

179,956

MEASURING DEVICE

John C. Setecka, Chicago, Ill.

Application August 15, 1955, Serial No. 37,454

Term of patent 14 years

(Cl. D44—29)

Fig. 1

Fig. 2

Fig. 3

Fig. 4

Figure 1 is a perspective view of a measuring device showing my new design;

Figure 2 is a top plan view thereof;

Figure 3 is an elevational view of one side thereof; and

Figure 4 is a bottom plan view.

The essential features of the design reside in those portions shown in full lines.

I claim:

The original design for the measuring device, as shown and described.
